UNITED STATES PATENT OFFICE

FRANK R. BELLUCHE, OF RACINE, WISCONSIN

BRONZING MACHINE

Application filed June 13, 1928. Serial No. 285,030.

This invention relates to certain new and useful improvements in bronzing machines designed to apply bronze to printed matter, the bronze adhering only at the places where 5 the ink or size is moist.

In bronzing machines of this character and especially the type known in the art as "rotary bronzers" the work or sheet is carried by a roll or cylinder beneath a supply of 10 bronzing material and past a pad which rubs the bronze into the work and then past cleaning rolls which remove all excess bronze. As will be readily apparent the proper adjustment of the cleaning rolls with respect 15 to the work is of extreme importance and heretofore has entailed the tedious task of separately adjusting both ends of the rolls and this invention has as an object the provision of an improved mounting for the 20 cleaning rolls whereby they may be adjusted from one side of the machine, retaining at all times a position parallel with the axis of the cylinder.

Another object of this invention resides in 25 the provision of improved cleaning bars for the cleaning rolls which are automatically adjusted with the rolls so as to just touch their surfaces, and thus insure the efficient removal of bronze therefrom which is withdrawn from the machine by an exhauster.

A further object of this invention resides 30 in the provision of an improved bronzing machine which is of extremely simple construction to insure the highest possible quality of work with increased speed.

With the above and other objects in view which will appear as the description proceeds, my invention resides in the novel construction, combination and arrangement of 35 parts substantially as hereinafter described and more particularly defined by the appended claims, it being understood that such changes in the precise embodiment of the 40 herein disclosed invention may be made as come within the scope of the claims.

In the accompanying drawings, I have 45 illustrated one complete example of the physical embodiment of my invention constructed according to the best mode I have

so far devised for the practical application of the principles thereof, and in which:

Figure 1 is a side, elevational view, with parts broken away and in section, of a bronzing machine embodying my invention;

Figure 2 is a view similar to Figure 1 of 55 the opposite side of the machine;

Figure 3 is an enlarged, fragmentary, detail view of one end of the cylinder cleaning roll illustrating the means for adjusting the 60 same;

Figure 4 is an enlarged view, partly in section and partly in elevation, taken through Figure 3 on the plane of the line 4-4; and

Figure 5 is a perspective view of one of the 65 cylinder cleaning rolls and its cleaning bar, said roll and bar being illustrated apart from the machine.

Referring now more particularly to the accompanying drawings, in which like numerals 70 designate like parts throughout the several views, 5 represents the side frame members of the machine which are preferably skeletonized for economy of material and weight. A work feeding cylinder 6 is rotatably mounted 75 between the frame members near their upper central portions by a shaft 7 journaled in bearings 8, the cylinder 6 having a gear 9 at one end meshing with the gear 10 of a work delivery cylinder 11 mounted in advance of 80 the cylinder 6 but on a lower plane on a shaft 12 journaled in bearings 13 similar to the bearings 8 of the cylinder 6. The gear 10 of the delivery cylinder is driven by a pinion gear 14 fixed to a driven shaft 15 mounting a 85 pulley 16 driven from a motor or other source of power, not shown, through a belt 17.

The cylinders are preferably hollow for economy of weight and material and have a transverse channel or recess 18 in their circumference in which gripper fingers 19 are 90 mounted on a shaft 20 to clamp, between them and the inclined or beveled edge 21 of the cylinder channel 18, the leading edge of the work 22 to be bronzed. Suitable mechanism, 95 not shown, opens the grippers 19 when in line with a stationary work feeding table 23 so that the work 22 enters therebetween, the grippers being then operated to engage the work in the manner illustrated in Figure 1. 100

The cylinder 6 then carries the work past the bronzing mechanism in the manner later described and transfers it to the delivery cylinder. Inasmuch as the gripper and transfer mechanism form the subject matter of my co-pending application, Serial Number 285,033, filed June 13, 1928, the same have not been shown or described in detail.

The work may be fed by hand to the roll 6 or may be conveyed automatically from a press by a feeder consisting of endless belts 24 having their discharge ends trained about rollers 26 juxtapose the plate or table 23. As the work passes over the cylinder 6, bronze 26 is sprayed thereon from a bin or source of supply 27 by a rotating spraying brush 28 which closes the bottom of the bin and throws bronze onto the work, as indicated at 29, a guard plate 30 being disposed in advance of the brush 28, as illustrated in Figure 1. The work then passes beneath a bronzing pad or member 31 carried by a canvas or mounting member 32 having its ends oppositely wound about a pair of spaced rotatably mounted rods or drum members 33, as at 34, crank arms 35 being fixed to the members 33 and connected by a contractile spring 36 which tends at all times to wind the ends of the canvas 32 on the members 33 and holds the pad taut against the surface of the cylinder 6.

The bronzing pad is reciprocated transversely of cylinder 6 in a plane parallel to its axis by a rack member 37 which is reciprocally mounted on a pair of aligned bearings 38 and meshes with a gear wheel 39 fixed to a shaft 40 journaled in bearings 41 fixed to the frame 5 and mounting gears, not shown, concealed within gear housing 42. The gears within the housings 42 mesh with rack teeth, not shown, cut in the adjacent ends of the rods or drums 33 which project beyond the frame 5, as more at length described and illustrated in my co-pending application, Serial Number 285,032 filed June 13, 1928. Rack 37 is reciprocated by a pitman 43 pivotally connected therewith, as at 44, and having one end connected with an eccentric 45 fixed on the driven shaft 15.

As the work leaves the bronzing pad, it passes a plurality of bronze removing rolls 46 which remove the excess of bronze from the work so that when it is discharged from the machine onto a delivery belt or conveyer 47 by the delivery roll 11 only the printed matter is bronzed. The cleaning rolls 46 being of identical construction, but one will be described in detail and the reference characters applied to all. Each roll 46 is preferably formed of cloth mounted on a shaft 48 the ends of which are journaled in bearing members 49 having depending skirts or mounting plates 50 which engage the outer surface of the frames 5, in the manner best illustrated in Figure 3, the skirts 50 being provided with longitudinal grooves 51 which slidably receive

keys or gibbs 52 secured to the side frames to permit longitudinal movement of the bearing members radially towards and away from the axis of the cylinder 6. The inner face of the skirts is further provided with spaced transversely positioned shoulders 53 and 54 which engage the periphery of adjusting discs 55 at opposite sides.

The discs 55 have eccentrically disposed sleeves or collars 56 which are journaled in apertures 57 in the frames and are splined on a shaft 58 extended across the machine, as at 59, so that rotation of the shaft by a suitable crank, not shown, applied to its squared end 60 extended beyond one bearing 80 skirt 50 causes a simultaneous rotation of the discs 55 at both sides of the machine, which, being eccentrically mounted on the shaft, produces a longitudinal movement of the bearing members to consequently adjust the roll. The bearings are held in their adjusted positions by jam nuts 61 threaded on the ends of the shaft 58 to bind the bearings against the frame 5 and consequently hold the shaft against shifting.

Each cleaning roll is provided with a cleaning bar 60' which extends across the entire length of its roll and is pivotally mounted on a shaft 61', the ends of which are fixed in the side frames 5. The cleaning bars of each roll are identical and are preferably cast to substantially arcuate shape in cross section having their edge 62 in close proximity with the periphery of their respective cleaning rolls so that they remove all excess bronze therefrom. A lever or arm 63 is cast integral with each cleaning bar or otherwise secured adjacent one end thereof and has one end of a contractile spring 64 connected therewith, the other end of which is suitably secured to the side frame, to at all times urge the edge 62 of the cleaning bar toward the periphery of its roll, movement of the bar towards the roll being restrained by a cam 65 carried by the bearing members 49 on the side of the machine at which the adjustment of the rolls is effected.

A roller 66 rotatably mounted on a stud 67 extended from the cleaning bars engages the face of the cams 65 which is inclined outwardly and downwardly with respect to the axis of the cylinder 6, so that as the rolls become worn through use and are readjusted closer to the cylinder, the inclination of the face of the cams permits the springs 64 to move the cleaning bars towards the periphery of the rolls to at all times maintain the edge 62 thereof at the proper position with respect thereto.

The side of the frame 5 adjacent the squared ends 60 of the shafts 58 is apertured, as at 70, where the shafts of the rolls 46 pass therethrough, an area sufficient to permit a view of the contact of the rolls with the cylinder 6, so that a feeler or other adjusting mem-

ber, not shown, may be inserted between the rolls and the cylinder to aid in their adjustment, as will be readily apparent. The frame 5 at the other side of the machine has a series of slots, not shown, through which the roll shafts pass, the slots being tightly closed by the skirts or flanges 50 of the adjacent bearings.

The rolls 46 are all rotated in the same direction at a uniform speed by a sprocket chain 71 drivingly engaged with sprocket wheels 72 fixed to the extended ends of the shafts 48 opposite the side of adjustment, the sprocket chain being trained about a sprocket wheel 73 fixed to the driven shaft 15. The sprocket chain is held taut and in engagement with the two inner sprocket wheels by an idler sprocket 74 which is carried by a conventional adjusting device 75.

20 A cleaning roll structure 76 similar to the rolls 46 is mounted above the delivery roll or cylinder 11 to clean the under surface of the work or sheet passing through the machine.

25 From the foregoing description taken in connection with the accompanying drawings it will be readily apparent to those skilled in the art to which an invention of this character apertains that I provide an improved 30 means for adjusting the cleaning rolls of a bronzing machine, which may be manipulated from one side of the machine and in which the cleaning bars of the rolls are automatically adjusted.

35 What I claim as my invention is:

1. In a bronzing machine having a work receiving surface, a cleaning roll adapted to clean the work passed over the surface, a cleaning bar cooperating with the cleaning roll to remove excess bronze from the roll, means independent of the cleaning roll for maintaining the cleaning bar in operative relation thereto, and means for simultaneously adjusting the cleaning roll and the 45 cleaning bar.

2. A bronzing machine including a cylinder adapted to carry work to be bronzed through the machine, a cleaning roll, bearing members rotatably mounting the roll at each end thereof, a cleaning bar adapted to remove excess bronze from the cleaning roll, means for simultaneously moving the bearing members at each end of the cleaning roll to adjust the same with respect to the cylinder, and cooperating means carried by one bearing member and the cleaning bar for adjusting the cleaning bar with respect to the periphery of the roll.

3. In a bronzing machine having a pair of side frames and a cylinder adapted to carry work to be bronzed through the machine, a cleaning roll for removing excess bronze from the work, bearing members adjustably secured to the side frames to rotatably mount the cleaning roll, a cleaning bar for remov-

ing excess bronze from the cleaning roll, means for adjusting the cleaning roll with respect to the cylinder frame on one side of the machine, a cam carried by one bearing member, and means carried by the cleaning 70 bar and engageable with the cam whereby adjustment of the cleaning roll simultaneously adjusts the cleaning bar with respect to the periphery of the roll.

In testimony whereof I have hereunto af- 75 fixed my signature.

FRANK R. BELLUCHE.
